Primary Examiner — Elizabeth J Oswecki(74) *Attorney, Agent, or Firm* — Payam Moradian(57) **CLAIM**

The ornamental design for a snowman clip, as shown and described.

DESCRIPTION

FIG. 1 is a perspective view of a snowman showing my new design;

FIG. 2 is a front view thereof;

FIG. 3 is a rear view thereof;

FIG. 4 is a left side view thereof; and,

FIG. 5 is a right side view thereof.

The broken lines shown in the drawings represent portions of the snowman that form no part of the claimed design. All surfaces not shown form no part of the claimed design.

1 Claim, 3 Drawing Sheets*FIG. 1*

FIG. 2

FIG. 3
